DESIGN.

J. DRAYCOTT.

LACE.

APPLICATION FILED JAN. 11, 1922.

61,223.

Patented July 18, 1922.

Inventor
John Draycott
By his Attorney
S.S. Suggs

Certificate of Correction.

It is hereby certified that Design Letters Patent No. 61,223, granted July 18, 1922, upon the application of John Draycott, of Pawtucket, Rhode Island, for a "Design for Lace," were erroneously issued to the inventor, said Draycott, whereas said Letters Patent should have been issued to Phenix Lace Mills, of Phenix, Rhode Island, a Corporation of Rhode Island, as shown by the records of assignments in this office; and that the said Letters Patent should be read with this correction therein that the same may conform to the record of the case in the Patent Office.

Signed and sealed this 8th day of August, A. D., 1922.

[SEAL.]

KARL FENNING,

Acting Commissioner of Patents.

UNITED STATES PATENT OFFICE.

JOHN DRAYCOTT, OF PAWTUCKET, RHODE ISLAND.

DESIGN FOR LACE.

61,223.

Specification for Design.

Patented July 18, 1922.

Application filed January 11, 1922. Serial No. 164. Term of patent 3½ years.

To all whom it may concern:

Be it known that I, JOHN DRAYCOTT, a citizen of the United States, residing at Pawtucket, in the county of Providence and State of Rhode Island, have invented a new, original, and ornamental Design for Laces, of which the following is a specification, reference being had to the accompanying drawing, forming part thereof.

The figure is a view of a section of lace, showing my new design.

I claim:

The ornamental design for a lace, as shown.
